(57) **CLAIM**

The ornamental design for a multi-chamber cable stacker as shown and described.

DESCRIPTION

FIG. 1 is a front isometric view of a multi-chamber cable stacker;

FIG. 2 is another front isometric view of the multi-chamber cable stacker of FIG. 1;

FIG. 3 is a front view of the multi-chamber cable stacker of FIG. 1;

FIG. 4 is a rear view of the multi-chamber cable stacker of FIG. 1;

FIG. 5 is a left side view of the multi-chamber cable stacker of FIG. 1;

FIG. 6 is a right side view of the multi-chamber cable stacker of FIG. 1;

FIG. 7 is a top view of the multi-chamber cable stacker of FIG. 1;

FIG. 8 is a bottom view of the multi-chamber cable stacker of FIG. 1;

FIG. 9 is a front view of a multi-chamber cable stacker having five chambers.

FIG. 10 a front view of a multi-chamber cable stacker having seven chambers; and,

FIG. 11 a front view of a multi-chamber cable stacker having eight chambers.

The broken lines represent structure or features that form no part of the claimed design.

1 Claim, 8 Drawing Sheets
